UNITED STATES PATENT OFFICE

LOUIS A. DILLER, OF FOLLANSBEE, WEST VIRGINIA, ASSIGNOR TO SHEET METAL SPECIALTY COMPANY, OF PITTSBURGH, PENNSYLVANIA, A CORPORATION OF WEST VIRGINIA

DESIGN FOR A BIRD FEEDER OR SIMILAR ARTICLE

Application filed November 7, 1931. Serial No. 41,647. Term of patent 14 years.

To all whom it may concern:

Be it known that I, LOUIS A. DILLER, a citizen of the United States, residing at Follansbee, in the county of Brooke and State of West Virginia, have invented a certain new, original, and ornamental Design for Bird Feeder or Similar Article, of which the following is a specification, reference being had to the accompanying drawings, forming a part hereof.

Figure 1 is a perspective view; and

Figure 2 is a side elevation on a slightly smaller scale of a bird feeder or similar article, showing my new design.

I claim:

The ornamental design for a bird feeder or similar article, as shown.

In testimony whereof I have hereunto subscribed my name this 5th day of November, 1931.

LOUIS A. DILLER.
